Obed B. Billman
Attorney

UNITED STATES PATENT OFFICE.

FRANK A. HIGGINS, OF BELLEVUE, OHIO.

LIQUID-FUEL BURNER.

Application filed January 19, 1923. Serial No. 613,761.

To all whom it may concern:

Be it known that I, FRANK A. HIGGINS, a citizen of the United States, residing at Bellevue, in the county of Sandusky and State of Ohio, have invented certain new and useful Improvements in Liquid-Fuel Burners, of which the following is a specification.

My invention relates to improvements in liquid fuel burners, and more particularly to that class or type which are especially designed and adapted for vaporizing a liquid fuel, such as common kerosene or so-called "coal-oil."

The primary object is to provide a generally improved burner of the type or class indicated which will be exceedingly simple in construction, cheap of manufacture and efficient in use.

A further and very important object is the provision of an improved retort or vaporizing head, together with an improved form and arrangement of burner and base conjointly forming a vapor supply chamber, and an improved vapor distributing head and air inlet or mixer opening in the base adapted to cooperate with the vapor distributing head, the latter being provided with an improved vapor distributing plate or element whereby the vapor or gaseous fuel is distributed to produce an extensive and intensive flame from the burner.

A still further object is the provision of improved liquid fuel feeding and distributing mechanism, together with simple and efficient means for initially heating the retort.

A still further object is the provision of a liquid fuel burner having its parts so arranged and disposed relative to each other as to permit of ready assemblage or disassembly for cleaning or repair.

A still further object is the provision of an improved heating burner admirably adapted for use in heating stoves, the superposed retort being adapted also to divert the flames from the burner outwardly and upwardly toward and along the walls of the fire box or stove in an efficient manner.

With the above mentioned and other ends in view, the invention consists in the novel construction, arrangement and combination of parts, hereinafter described, illustrated in one of its embodiments in the accompanying drawings and particularly pointed out in the appended claims.

Referring to the drawings, forming a part of this specification, Figure 1 is a fragmentary side elevation, partly in section, of the conventional form of heating stove equipped with a liquid fuel burner constructed in accordance with this invention.

Fig. 2, an enlarged fragmentary side elevation, partly in section, of the improved burner, detached.

Similar numerals of reference designate like parts throughout all the figures of the drawings.

The improved liquid fuel burner comprises a suitable base surmounted by a suitable burner plate, said base, in the present instance, comprising a flat disc shaped member 1, provided with an annular inclined wall portion 1^a, said wall, in the present instance, terminating in a flange 1^b, forming an opening 1^c. For convenience in assembling and disassembling for inspection or repair, the base is made of the separate parts 1 and 1^a and the opening 1^c is closed or covered by the disc shaped burner plate 2.

The burner plate 2 may be of any suitable and convenient construction and in the present instance it is provided with a series of relatively thin slot openings 2^a, through which the subjacent vapor in the vapor chamber is adapted to be fed to provide a suitable flame in the form of a series of correspondingly extending jets or ribbons of flame. When the base and burner plate are made separate, as shown, the burner 90 may be sealed by means of suitable sealing material 2^b, and the lower joint between the annular wall 1^a and the base disc 1 may likewise be sealed by means of suitable sealing material 1^d.

When mounted in the base of 95 the fire box 3, of an ordinary stove the burner is mounted above the ash pit 3^a, as indicated most clearly in Fig. 1 of the drawings.

The base and the fire plate conjointly 100 form an air mixing and vapor supply chamber 4, for receiving the vapor generated in the retort, as hereinafter referred to. As a means of admitting air into the chamber 4 to mix with or dilute the vapor and support the combustion through the openings in the burner plate, said base is provided with a central air supply or mixer opening 1^e. The burner plate is provided with a central opening formed by means of a depending boss or sleeve head 1^f, the opening 1^f being preferably threaded to remov-

ably receive and contain a central conduit or stem consisting, in the present instance, of an upper part or section 5, and a lower part or section 5^a. The upper end of the 5 conduit or stem is provided with a retort consisting of a base member 6, and a concavo-convex shaped member or dome 6^a, conjointly forming a vaporizing chamber 6^b.

The outer edge of the retort base member 10 6 is preferably depressed to provide an annular channel 6^c, to receive the liquid fuel or oil to be vaporized and the plates 6 and 6^a may be connected by means of securing elements or screws 6^d, and an interposed 15 gasket 6^e.

As a means of initially heating the retort or head, the central portion of the burner 2 is preferably provided with a cup shaped portion 2^c, surrounding the stem or conduit 20 5 and preferably supplied with a filling of asbestos or other suitable material, and as a means of supplying such filling material 2^d with liquid fuel, the cup 2^c is placed in communication with a liquid fuel supply 25 pipe 7, leading outwardly and upwardly and adapted to be controlled by means of a valve 7^a, leading to a branch head 7^b, communicating with a common supply pipe 8, leading to a suitable tank or reservoir, the 30 common supply pipe being provided with a sleeve 9, provided with a sight opening 9^a, for observing the feeding of the oil.

As a means of supplying the retort with liquid fuel, a second feed or supply pipe 35 10, is provided, the upper end of the feed pipe 10 within the retort and just above the base member 6, being preferably bent outwardly and downwardly as at 10^a, to initially supply the annular channel 6^b, said 40 second pipe extending downwardly through the conduit stem and thence outwardly and being provided with a control valve 10^b, likewise communicating with the branch head 7^b. After the retort is sufficiently 45 heated to vaporize any liquid fuel introduced therein, it will be apparent that the vapor will be fed downwardly through the vapor supply stem, and as a means of uniformly and properly distributing the vapor, the lower end of the stem is provided 50 with a vapor supply head 5^b, said head, in the present instance being provided with outwardly extending ports 5^c, and as a means of distributing the vapor outwardly within 55 the chamber and to mix with the incoming air supply through the openings 1^c, said supply head is preferably provided with a spreader plate 5^d. If desired, the spreader plate 5^d may be provided with a series of 60 openings 5^e. As a means of preventing any back flash of the flames on the burner plate as well as more evenly and uniformly distributing the vapor to the openings in the 65 burner plate, a wire gauze or screen 11 is preferably mounted within the underside

of the burner plate, as shown most clearly in Fig. 2 of the drawings.

Having thus described one of the embodiments of my invention, without having attempted to set forth all the forms in which it may be made, or all the modes of its use, what I claim and desire to secure by Letters Patent is,—

1. A liquid fuel burner, comprising a removable vapor supply stem terminating in 75 a two-part retort, a burner plate provided with a base and conjointly with the latter forming a vapor supply chamber, said base having an air supply opening below said vapor supply stem, and a vapor supply head 80 on said vapor supply stem above said air supply opening of said base.

2. A liquid fuel burner, comprising a two-part retort provided with a subjacent conduit stem, a burner plate provided with a separate base and conjointly with the latter forming a vapor supply chamber, said base being provided with an air supply port below said conduit stem, and a vapor supply head and spreader plate carried by 90 said conduit stem above said central air supply opening of said base.

3. A liquid fuel burner, comprising a retort provided with a subjacent conduit stem, a burner plate provided with a base 95 and conjointly therewith forming an air mixing and vapor supply chamber, said base being provided with a central air supply opening below said conduit stem, and a vapor supply head carried by said conduit stem in said air mixing and vapor supply chamber above said central air supply opening of said base.

4. A liquid fuel burner, comprising a fuel and vapor supply stem terminating in a 105 retort, a burner plate provided with a base conjointly therewith forming a vapor supply chamber and having a central air supply opening below said fuel and vapor supply stem, a vapor supply head on said fuel and vapor supply stem above said air supply opening of said base, and a vapor spreader disc plate above said opening and vapor supply head and below said burner plate.

5. A liquid fuel burner, comprising a base provided with a burner plate and conjointly therewith forming a vapor supply chamber, said base being provided with a central air inlet opening, a conduit stem extending upward above said burner plate and provided with a retort, a vapor distributing head above said air inlet opening, means for supplying liquid fuel to said retort, and means beneath said burner plate for preventing back fire from said burner plate into said supply chamber.

6. A liquid fuel burner, comprising a burner plate provided with a central opening, a base connected to and supporting 130

said burner plate and having a central air supply opening below said opening of said burner plate, a stem in said opening of said burner plate and projecting above the latter 5 terminating in a retort, said stem terminating at its lower end in a vapor supply head and a vapor spreader plate arranged above said air supply opening of said base, and an oil supply pipe extending upwardly through 10 the conduit stem to distribute the oil within said retort.

7. A liquid fuel burner, comprising an air and vapor supply chamber provided at its top with a burner plate and at its bottom 15 with a central air inlet opening, a tu-

bular stem extending through the central portion of said burner plate terminating at its top in a retort surmounting said burner plate, said tubular stem terminating at its base in a vapor supply head above said air 20 inlet opening of said base, a liquid fuel supply pipe extending through said stem and terminating in said retort, and a priming cup in said burner plate below said retort and provided with a priming conduit 25 pipe.

In testimony whereof I have affixed my signature.

FRANK A. HIGGINS.
